Patented Dec. 14, 1965

203,175

AWNING

Burton L. Siegal and Nicholas S. Kategianis, Chicago, Ill.,
assignors to Kenron Awning and Window Corporation,
Chicago, Ill., a corporation of Illinois

Filed Mar. 16, 1964, Ser. No. 79,010

Term of patent 14 years

(Cl. D21—6)

Fig. 1

Fig. 2

Fig. 4

Fig. 3

FIGURE 1 is a top perspective view of an awning showing our new design;

FIGURE 2 is a bottom view;

FIGURE 3 is a side elevational view; and

FIGURE 4 is a top perspective view of another embodiment of the design of FIGURE 1 wherein a generally vertical visor is provided on the front of the awning.

The dominant features of our design are shown in the full lines.

We claim:

The ornamental design for an awning, substantially as shown and described.
